UNITED STATES PATENT OFFICE.

ABEL MAGUI, OF NEW YORK, N. Y., ASSIGNOR TO ROYAL ART GLASS CO., A CORPORATION OF NEW YORK.

DESIGN FOR A BASE FOR LIGHTING FIXTURES OR SIMILAR ARTICLES.

Application filed July 9, 1924. Serial No. 10,101. Term of patent 3½ years.

To all whom it may concern:

Be it known that I, ABEL MAGUI, a citizen of the United States, and a resident of the city of New York, county of Bronx, and State of New York, have invented a new, original, and ornamental Design for Bases for Lighting Fixtures or Similar Articles, of which the following is a specification, reference being had to the accompanying drawing, forming a part hereof.

In these drawings:

Fig. 1 is a top view of the base for lighting fixtures or similar articles, the part shown in full line outline being ornamented in the same manner as the part more fully illustrated.

Fig. 2 is a side elevation showing the outline of the base for lighting fixtures or similar articles.

I claim:

The ornamental design for a base for lighting fixtures or similar articles substantially as shown and described.

ABEL MAGUI.
